JONATHAN MOORE AND WILLIAM WILKINSON, OF BROOKLYN, NEW YORK,
ASSIGNORS TO JONATHAN MOORE AND A. HORTON, OF SAME PLACE.

Design No. 4,807, dated April 11, 1871.

DESIGN FOR AN ORNAMENT FOR FOUNTAINS, &c.

The Schedule referred to in these Letters Patent and making part of the same.

We, JONATHAN MOORE and WILLIAM WILKINSON, of Brooklyn, in the county of Kings, State of New York, have invented and produced a new and original Design for Ornaments on Fountains and Vases, of which the following is a specification.

Our design we may distinguish for convenience by the term "vine." It is composed of heavy vines intertwined with lobed leaves heavily fluted, and curled at the points.

The leaves alternate as follows:

A large leaf in one convolution or turn of the vine, and two small ones lying in positions opposite to each other in the next convolution. It is laid upon a plain ground, and above it is a wavy edge, which forms the margin of the vase or the dripping-edge of the fountain when it is used as a fountain.

The contours and arrangements of the several members are fully represented in the accompanying drawings, to which reference is made.

Figure 1 is an outline of the contours of the several members, and

Figure 2 is a photographic illustration, giving a fuller view of the complete work.

The work will be ordinarily made in cast-iron, painted, bronzed, or otherwise protected; but the design is equally applicable to work in other materials.

We claim as our invention—

The design herein shown, which we may denominate vine, for ornamentation of fountains and vases.

In testimony whereof we have hereunto set our names in presence of two subscribing witnesses.

JONATHAN MOORE.
WILLIAM WILKINSON.

Witnesses:

JAMES DENBIGH,
BENJAMIN MORRISON.
